UNITED STATES PATENT OFFICE

161,231

PLANT PROTECTOR

Edward V. Alvarez, Los Angeles, Calif., assignor
to The Plas-Tex Corporation, Los Angeles,
Calif., a corporation of Nevada

Application August 22, 1949, Serial No. 4,639

Term of patent 3½ years

(Cl. D35—2)

To all whom it may concern:

Be it known that I, Edward V. Alvarez, residing at Los Angeles, in the county of Los Angeles and State of California, have invented a new, original, and ornamental Design for a Plant Protector, of which the following is a specification, reference being had to the accompanying drawing, forming part thereof, in which:

Fig. 1 is a side elevation of a plant protector, showing my new design;

Fig. 2 is a top plan view of the same;

Fig. 3 is a bottom plan view of the same; and

Fig. 4 is a fragmentary, vertical, medial sectional view taken on the line 4—4 of Fig. 1 looking in the direction indicated by the arrows.

I claim:

The ornamental design for a plant protector, as shown.

EDWARD V. ALVAREZ.
